UNITED STATES PATENT OFFICE.

VIVIAN B. FULLER, OF INDIANAPOLIS, INDIANA.

AUTOMATIC WINDING DOOR-BELL.

SPECIFICATION forming part of Letters Patent No. 755,568, dated March 22, 1904.

Application filed May 11, 1903. Serial No. 156,591. (No model.)

To all whom it may concern:

Be it known that I, VIVIAN B. FULLER, a citizen of the United States, residing at Indianapolis, in the county of Marion and State of Indiana, have invented certain new and useful Improvements in Automatic Winding Door-Bells, of which the following is a specification.

This invention relates to improvements in door-bells in which a gong is sounded by blows from a spring-actuated hammer; and the object of the invention is to provide means by the opening and closing of the door for automatically winding the spring.

The object also is to provide a regulative means or governor which will prevent the overwinding of the spring.

I accomplish the objects of the invention by the mechanism illustrated in the accompanying drawings, in which—

Figure 1 is a detail in horizontal section of a door and its casing, showing my invention applied thereto; Fig. 2, a front or outside view of the ringing device with the gong and outer plate of the frame removed to reveal the inside mechanism; Fig. 3, a back side view of Fig. 2; and Fig. 4, a section on the dotted lines 4 4 of Figs. 2 and 3.

Like characters of reference indicate like parts throughout the several views of the drawings.

5 is a door, 6 the door-casing, and 7 the hinges by which the door is hinged to the casing.

8 is a spindle or short shaft which is mounted in a frame comprising a pair of plates 9, (see Fig. 4,) connected by posts 10. This frame is secured to a base 11, which is fastened by screws 12 to the door. The spindle

40 8 has the sleeve 13 mounted loosely on its inner end and extending through the inner plate 9, so as to receive the ratchet-wheel 14, which is mounted in a fixed manner thereon. Fastened to the side of the wheel 14 is the

45 drum 15, within which is the band-spring 16, the inner end of which is fastened to the spindle 8 and its outer end to the inner wall of the drum, as shown in Fig. 4. Mounted loosely on the shaft 8 is the cog-wheel 17, which is separated from the drum and spring

by the washer-plate 18. Mounted in a fixed manner on shaft 8 is the ratchet-wheel 19, whereby through the action of the spring-actuated pawl 20, pivotally secured to wheel 17, the power from the band-spring is transmitted to the said cog-wheel. Mounted on the adjacent end of shaft 8 outside of the frame is the bell-gong 21. A means of winding up the spring 16 by hand is provided by grasping the gong and by means of it turning 55 the spindle 8, pawl 20, and ratchet-wheel 19, permitting the proper rotation.

22 is a pinion mounted on a shaft supported by the frame. The pinion is driven by engagement with wheel 17, and mounted on the same shaft with said pinion is the escapement-wheel 23, which is controlled by the anchor 24, mounted on a suitable adjacent shaft which also carries the rod 25, which terminates with the hammer 26. The latter is vibrated by the 70 above mechanism, thereby striking and ringing the gong. A longitudinally-adjustable shaft having the disk 27, said shaft being held by spring 28 in normal position with said disk under hammer-rod 25 to prevent the vibration of the latter, is moved by push-rod 29, terminating with a suitable button, so as to release the hammer-rod.

I will now describe the means for winding the spring 16 by the swinging of the door. 80 The action of the spring 16 on wheel 14 is resisted by the spring-actuated pawl 30; but obviously by rotating the wheel 14 in the direction permitted by its pawl drum 15, to which one end of spring 16 is fastened, will be 85 rotated, so as to wind up the spring.

31 is a drum mounted in a fixed manner on sleeve 13, to which it is secured by screw 32. The outer end of the sleeve has the annular flange 33, between which and the drum 31 is 90 the ratchet-wheel 34, having a hub on one side which is extended into the bore of the drum. This hub is mutilated on one side to receive a post 35, seated in sleeve 13. The adjustment of the wheel 34 on said sleeve is 95 limited by contact of the post with the ends of the hub mutilation. The diameter of said hub is enough less than that of the bore of the drum to allow the introduction of the coiled wire spring 36 between them. The in- 100

ner end of this spring is secured to the drum 31 and the outer end to the ratchet-wheel 34. (See Fig. 4.) When the tension on the band-spring 16 is less than the tension of spring 36, 5 a rotation of the ratchet-wheel 34 will in like measure rotate the drum 31, and thence through sleeve 13, ratchet-wheel 14, and drum 15 the spring 16 will be wound, the ratchet-wheel 34 and drum 31 acting through spring 10 36; but when the tension of spring 16 exceeds that of spring 36 the rotary movement of the ratchet-wheel 34 will not move the drum 31; but the wheel will oscillate within the limits fixed by its mutilated hub and post 35. The 15 desired maximum tension of spring 36 is given at the time of assembling the wheel and drum on sleeve 8.

Mounted upon the drum 31 is an additional drum 37, having an annular channel in which 20 is seated the coiled wire spring 38. One end of this spring is fastened to the plate 9 of the frame and the other end to the drum 37. Pivotally secured to the drum 37 is a pawl 39, which is pressed by spring 40 into engagement 25 with the teeth of the ratchet-wheel 34. Also secured to the drum in a rigid manner is the lever 41, to the outer end of which a chain 42 is fastened. The door is mortised in the manner shown in Fig. 1 to receive the 30 above-described winding-drums, and leading into this mortise from the back edge of the door is the bored hole 43, through which the chain 42 is threaded in the manner shown, and the end of the chain is made fast to the 35 door-frame by staple 44 or other suitable means. Preferably the mouth of the bore will be reinforced with a metal thimble 45 to prevent wear.

The opening of the door draws on the chain, 40 thereby shifting lever 41 and moving drum 37. Pawl 39, by engaging ratchet-wheel 34, moves the latter wheel, which through spring 36, drum 31, sleeve 13, wheel 14, and drum 15 winds spring 16 till tension of latter reaches 45 that of spring 36, when the continued opening of the door oscillates lever 41 and its drum and ratchet-wheel 34 without further winding of spring 16.

Spring 38 in drum 37 is for the purpose of 50 returning the drum and lever 41 to first position after release by the chain.

46 represents a washer.

The bell may be secured to the door-casing and the chain fastened to the door, where such 55 application is preferred.

Having thus fully described my invention, what I claim as new, and wish to secure by Letters Patent, is—

1. In a self-winding spring-actuated door-bell, the combination, with a spindle, of a sleeve mounted on the spindle, a drum mounted on the sleeve, a coiled spring having one end fastened to the spindle and the other end secured to said drum, a gong, a hammer, 60 means for vibrating the hammer by the force

of the spring to sound the gong, a hinged door, means connecting the door and sleeve whereby by the movement of the door the sleeve will be rotated to wind the spring, a spring-actuated overwinding-preventer to 70 prevent the overwinding and means for regulating the tension of the overwinding-preventer.

2. In a self-winding spring-actuated door-bell, the combination with a spindle, of a sleeve 75 mounted on the spindle, a drum mounted on the sleeve, a coiled spring having one end fastened to the spindle and the other end secured to said drum, a gong, a hammer, means for vibrating the hammer by the force of the 80 spring to sound the gong, a hinged door, means connecting the door and sleeve whereby by the movement of the door the sleeve will be rotated to wind the spring, an overwinding-preventer to prevent the overwinding of 85 the spring and means for changing the sensitivity or strain at which the overwinding means will operate.

3. In a self-winding spring-actuated door-bell, a spindle, a sleeve mounted loosely on 90 the spindle and adapted to rotate therewith in one direction only, a drum rotating with the sleeve, a spring fastened to the spindle at one end and to the drum at the other, a gong, 95 a hammer, means for vibrating the hammer by the force of the spring, a second drum mounted in a fixed manner on the sleeve, a ratchet-wheel mounted loosely on the sleeve, a spring flexibly connecting the ratchet-wheel and second drum, a door, and means by the swinging 100 of the door for oscillating the ratchet-wheel.

4. In a self-winding spring-actuated door-bell, a spindle, a sleeve mounted loosely on the spindle, means for preventing rotation of the sleeve except in one direction, a drum rotating with the sleeve, a spring fastened to the spindle at one end and to the drum at the other, means for vibrating the hammer by the force of the spring to ring the gong, a second 105 drum mounted in a fixed manner on the sleeve, 110 a ratchet-wheel mounted loosely on the sleeve, a spring flexibly connecting the ratchet-wheel and second drum, a third drum mounted on the second drum, a spring flexibly connecting the third drum with a fixed support, a pawl 115 carried by the third drum and engaging the teeth of the ratchet-wheel, a door, and a flexible tie connecting the third drum with the frame of the door whereby the swinging of the door will wind the first-named spring. 120

5. In a bell-ringing apparatus, a spindle, a sleeve loosely mounted thereon, a drum carried by the sleeve, a pawl and ratchet to allow rotation of the sleeve and drum in one direction only, a spring connected at one end 125 with the spindle and with the drum at the other, a second drum mounted in a fixed manner on the sleeve, a ratchet-wheel mounted loosely on the sleeve and having a mutilated hub taking into the bore of the second drum, 130

a coiled spring between the hub and rim of the drum having one end secured to the drum and the other to the ratchet-wheel, a post from the sleeve taking in the mutilation of the hub,
5 a third drum mounted upon the first drum, a spring flexibly connecting the third drum with a fixed support, a pawl pivoted to the third drum and engaging the teeth of the ratchet-wheel, a lever extension from the third drum,
10 a door, a frame to which the door is hinged

and a flexible tie connecting the lever extension with the door-frame.

In witness whereof I have hereunto set my hand and seal, at Indianapolis, Indiana, this 5th day of May, A. D. 1903.
